A. BREEN

ICE BOX

Filed Dec. 17, 1921

INVENTOR.
Anna Breen
E. C. Brandenburg
her ATTORNEY

UNITED STATES PATENT OFFICE.

ANNA BREEN, OF DYERSBURG, TENNESSEE.

ICE BOX.

Application filed December 17, 1921. Serial No. 523,071.

To all whom it may concern:

Be it known that I, ANNA BREEN, a citizen of the United States, residing at Dyersburg, in the county of Dyer and State of Tennessee, have invented certain new and useful Improvements in Ice Boxes, of which the following is a specification.

My invention relates to an improvement in ice-boxes.

10 This invention is especially devised for, and adapted to use on vehicles, such as automobiles, it being designed to rest upon the running-board.

15 The purpose is to make provision for carrying ice as well as perishable food, and in addition to this it provides drinking-water, and its top is convertible into a table, which may be utilized in any way.

20 The invention consists in a box having several compartments, one for ice, and the others for food, with means of communication between them to permit the cold air to circulate through the food compartments, a tank into which the water from the melting 25 ice drips, the bottom of the ice compartment being perforated to allow this water to splash back and forth against the ice with the motion of the vehicle, and to thereby assist in keeping the food compartments 30 at a low temperature at all times, covers, and (if desired) an extension to form with them a table.

In the accompanying drawings:—

Fig. 1 is a front view;

35 Fig. 2 is a longitudinal section;

Fig. 3 is a plan view with the covers removed;

Fig. 4 is a vertical transverse section.

40 A, represents the box divided preferably into an ice compartment 1, and two food compartments 2 on either side thereof.

45 A water tank 3 occupies the entire bottom, and is preferably made of galvanized iron or other metal, and the portion which extends beneath the ice compartment 1 has perforations 4. This compartment is also preferably lined with metal, and the melting ice drips through the perforations into the

water tank, and with the motion of the vehicle the water is splashed up and down through the perforations against the ice, thus keeping it at all times very cold, as well as the food compartments 2, 2.

50 A faucet 6 is provided for drawing off the drinking-water. Walls 7 may be erected a slight distance from the dividing partition between the compartments, and the space 8 therebetween may be filled, if desired, with insulating material, although this is not essential.

55 Hinged, or otherwise secured to the top, are covers or lids 9, of which there is one for each compartment; and hinged to one edge of these covers preferably is the extension-table 10, which normally is folded over the top of the lids or covers, as shown in Figs. 1 and 2; but when used as an extension-leaf for a table, it is folded out (as shown in Fig. 4) it being connected to the lid or cover by hinges 11 and brace 12 beneath the extension-table supports it when in its extended position as shown in Fig. 4.

60 This invention provides a much needed cooler for water and food for the automobile. It is simple, compact, and designed to fit the running-board. It is not only efficient for the purposes named, but, furthermore, is designed to form an extension-table 65 for dining and other purposes.

I claim:

65 A device of the character described including an elongated box divided transversely into compartments, a water tank extending beneath and forming the bottom of the several compartments thereof, the central compartment being an ice compartment and having a reticulated bottom to support the ice and allow the water to drain into the tank, and the water in turn from the tank to splash into the ice compartment, whereby 70 the ends of the water tank form a cooling medium for the different compartments of the box.

75 In testimony whereof I affix my signature.

ANNA BREEN.
